(57) **CLAIM**

The ornamental design for a tie gripper finger, as shown and described.

DESCRIPTION

FIG. 1 is a top perspective view of the present tie gripper finger;

FIG. 2 is a left side view of same, the sides being mirror images of each other;

FIG. 3 is a front view of the gripper finger of FIG. 1;

FIG. 4 is a rear view of same;

FIG. 5 is a top view of the gripper finger of FIG. 1; and,

FIG. 6 is a bottom view of same.

The structure shown in broken lines is for environment purposes only and does not form part of the claimed invention.
